APPARATUS FOR FLAME SPRAYING SURFACES OF VARYING DIAMETERS

Albert J. Thoma, Mountain View, Cornelius J. Bogert, Jr., Fair Lawn, and William F. Brown, Butler, N.J., assignors to Thiokol Chemical Corporation, Bristol, Pa., a corporation of Delaware

Filed Aug. 16, 1960, Ser. No. 49,904
6 Claims. (Cl. 118—318)

The present invention relates to an improved apparatus for uniformly coating surfaces and more particularly to coating surfaces with a flame spray of molten solids, such as refractory and erosion resistant materials and metals.

While the apparatus of the present invention may have other applications, it is particularly effective for coating the inside surfaces of hollow rocket motor casings. Such casings may be constructed of a thin gauge metal, or as a composite section of connected tubes, and have cylindrical, spherical, conical or other curved sections concentric about an axis of revolution. A refractory coating is desirable between the metal casing and fuel in rocket engines to at least partially insulate the metal casing from the high temperature of the burning fuel and to resist the erosion produced by the flow of gases at high velocity. A number of different refractory materials have been used to coat the interior of rocket engine casings, but one material which has been found to be especially effective for this purpose is a metal oxide described and claimed in U.S. Letters Patent 2,707,691, issued to William M. Wheildon on May 3, 1955. This material is supplied in solid form and must be melted and atomized to apply it in a uniform layer. To this end, a rod of the material may be subjected to a torch flame which melts and atomizes the material to form molten particles and the particles are projected by the blast of the flame onto the surface to be coated where the molten particles solidify. Also, in some rocket engines it is necessary to apply a thin coating of metal to the rocket engine casing to provide a suitable bonding surface for the refractory material.

One of the objects of the present invention is to provide an apparatus for applying a molten atomized coating uniformly on a surface of varying radial distance about an axis of revolution.

Another object is to provide an apparatus for relatively moving a flame spraying nozzle and surface to be coated so as to cause the nozzle to follow the irregular contour of the surface at the same distance therefrom.

Another object is to provide an apparatus for applying a flame spray coating on a curved surface in a helical path at a constant linear rate and pitch.

Another object is to provide an apparatus of the type indicated for flame spraying a uniform coating on the inside surface of a rocket motor casing.

Still another object is to provide an apparatus of the type indicated which is of relatively simple and compact construction, economical to manufacture and one which is reliable in operation.

These and other objects will become more apparent from the following description and drawings in which like reference characters denote like parts throughout the several views. It is to be expressly understood, however, that the drawings are for the purpose of illustration only and are not a definition of the limits of the invention, reference being had for this purpose to the appended claims.

In the drawings:

FIGURE 1 is a perspective view of an apparatus incorporating the novel features of the present invention which adapt it to uniformly coat a surface having varying radial dimensions about an axis of rotation;

FIGURE 2 is a diagrammatic view of a control mecha-

2

nism which illustrates the principle of varying the speed of rotation of the workpiece and rate of lead of the nozzle in proportion to changes in the radius of the surface to apply the coating at a constant rate in a helical path of uniform pitch;

FIGURE 3 is a perspective view of the unit for feeding the solid coating material and a combustible mixture to the flame spray nozzle;

FIGURE 4 is a diagram illustrating the variation in the 10 rotative speed of the workpiece and lead of the nozzle proportional to the radius of the surface to maintain a helical spray pattern of constant pitch;

FIGURE 5 is a perspective view of the controls used in a commercial embodiment of the invention;

FIGURE 6 is a perspective view showing an indicating 15 mechanism for resetting the nozzle to a precise position where a coating operation has been stopped; and

FIGURE 7 is an end elevational view showing the 20 flame spray nozzle for applying a coating to the surface of a regeneratively cooled type of rocket engine.

Referring now to the drawings, FIGURES 1 and 2 illustrate an apparatus incorporating the present invention, but showing a simplified drive and control mechanism to illustrate the principle of the invention. The apparatus operates automatically to compensate for variations in the radius of the surface from its axis of rotation to maintain the flame spray nozzle at the same distance from the surface, a constant relative speed between the surface and nozzle, and relatively move the nozzle and 30 surface to produce a helical spray pattern on the surface of constant pitch.

As illustrated in FIGURE 1, the apparatus 10 is generally similar to a lathe and has split bearings 11 and 12 arranged in spaced relation for supporting a workpiece 13, such as a rocket engine casing, for rotation about a fixed axis. As shown in FIGURE 1, the workpiece has a cylindrical section 13a and a conical section 13b at the end of the cylindrical section and forming the converging portion of a nozzle. The apparatus is particularly adapted to coat the inside surface of the workpiece 13 which may comprise a thin section of aluminum, stainless steel or other suitable material. It will be understood, however, that the surface of the rocket engine casing or other part to be coated may have other curved forms, either converging or diverging, which are concentric to a central axis about which the workpiece rotates. The workpiece 13 may be driven by any suitable variable speed drive for varying its rotative speed in proportion to variation in its radius to maintain a constant peripheral speed of the surface to be coated. In the embodiment illustrated in FIGURE 1, the variable speed driving means for the workpiece 13 comprises a driven element 14 mounted fast thereon and a driving element 15.

A flame spray nozzle 18 is mounted on the apparatus 55 for movement longitudinally of the workpiece 13 to coat its inner or outer surface. While the apparatus of the present invention may be used to apply other coatings, such as metals, it is particularly adapted for applying a ceramic, erosion resistant coating which is melted and 60 atomized by a flame and propelled by the flame in a diverging pattern. The flame spray nozzle 18 is located at one end of a long tube 19 having a mixing chamber 20 for combustible gases at its opposite end. Supply lines 22 and 23 are connected to the mixing chamber 20, see 65 FIGURES 1 and 3, for supplying a combustible mixture, such as oxygen and acetylene or natural or manufactured gas. Nozzle 18 comprises an orifice from which the combustible gases escape and burn to propagate a diverging flame. The tube 19 extends from the mixing chamber 70 20 which, in turn, is attached to a casing 24 having a mechanism for feeding the coating material 21. The feeding means comprises feed rolls 26 and 27 at the rear of

the mixing chamber for feeding the rod of coating material therebetween and an electric motor 25 and reduction gearing for driving the feed rolls.

The assembly of casing 24, mixing chamber 20 and tube 19 are supported on a rod 28 depending from and slideable through a horizontally movable carriage 29. The depending rod 28 extends through a sleeve 30 on the casing 24 and the rod and sleeve have a screw threaded engagement for initially adjusting the position of the tube 19 relative to the carriage 29. Thus, the flame spray nozzle 18 is supported at the end of tube 19 in spaced relation to the surface to be coated, is movable with the carriage 29 longitudinally of the hollow casing and is movable vertically relative to the carriage to adapt the nozzle to be maintained at a fixed distance from the surface. Carriage 29 is mounted to slide on a horizontally extending rod 34 mounted on brackets 35 projecting from a frame member on the apparatus 10. The carriage 29 comprises spaced bearing blocks 36 and 37 positioned between plates 38 and 39 and having a vertically arranged bearing 40 for slidably mounting the depending rod 28. Carriage 29 is slid along the fixed rod 34 longitudinally of the apparatus 10 by a hydraulic ram 41 having a cylinder 42 and piston rod 43 connected to the carriage. As the carriage 29 moves along the apparatus 10, the flame spray nozzle 18 at the end of tube 19 moves longitudinally of the surface of the workpiece to be coated.

The flame spray nozzle 18 is moved radially with respect to the surface to be coated by means of a cam follower 45 on the upper end of rod 28 which engages a contour cam 46. The cam follower 45 is in the form of a plate having a collar attached to the upper end of the rod 28 by a set screw, or the like, and a roller 47 projecting laterally therefrom and riding on the edge of the contour cam 46. The edge of contour cam 46 has a contour corresponding to the contour of the surface of the workpiece to be coated. For example, the contour cam 46 has a horizontal edge portion 46a corresponding to the cylindrical section of the surfaces of the workpiece 13 and an adjacent inclined section 46b of the same slope as the conical section of the workpiece. Thus, the nozzle 18 will be raised and lowered by contour cam 46 to follow the contour of the surface of the workpiece to be coated as it is moved longitudinally thereof to at all times maintain the nozzle 18 at the same distance from the surface to be coated.

In accordance with the present invention the rotative speed of the workpiece 13 and the rate of advance of the nozzle 18 are correlated by the movement of the cam follower 45 to maintain the same relative speed and a constant lead of the nozzle and surface to be coated at varying radial distances from the rotative axis to apply the coating uniformly in a helical pattern. As the periphery of the surface being coated at one radius is greater than the periphery of the surface at a smaller radius, the speed of rotation of the workpiece must be increased at the smaller radius, as indicated by curve marked RPM in FIGURE 4, to produce a uniform coating. Also, the lead or movement of the nozzle 18 longitudinally of the workpiece 13 must be varied with changes in the rotative speed of the workpiece as indicated by the curve marked LEAD to maintain a constant pitch of the helical path of the spray pattern. However, both of these speed changes are linear and inversely proportional to changes in the radius of the surface from the axis of rotation. Thus, the movement of the cam follower 45 as controlled by the contour cam 46 can be used as the control factor for varying both the speed of rotation of the workpiece 13 and lead of the nozzle 18 to produce a uniform coating on the surface.

The simplified control mechanism illustrated in FIGURE 2 is responsive to the movement of the cam follower 45 to vary the speed of the driving element 15 for driving the workpiece 13 and the hydraulic ram 41 for advancing the nozzle 18. The control comprises a depending rack 50 mounted on the cam follower 45 which meshes with a

splined shaft 51 to permit relative longitudinal movement. The splined shaft 51, in turn, meshes with a horizontally arranged rack 52 mounted to slide in spaced bearing guides 53. Horizontal rack 52 has a yoke 54 straddling a friction driving disc 55 mounted to slide on a splined shaft 56 driven by a constant speed electric motor 57 through reduction gearing. The periphery of the friction disc 55 engages the face of the driving element 15 and rotates the latter at a speed which varies in accordance with the radial position of the disc 55 from the axis of rotation of the disc. As the radial movement of the driving disc 55 exactly follows changes in the radius of the workpiece 13 through the contour cam 46, cam follower 45 and racks 50 and 52 the peripheral speed of the surface being coated is maintained constant. For example, the constant speed driving disc 55 may be positioned at the same radial distance from the axis of rotation of the disc 15 as the surface being coated is from its axis of rotation so as to maintain a constant speed of the surface relative to nozzle 18.

The speed of movement of carriage 29 operated by the hydraulic ram 41 depends upon the amount of hydraulic fluid supplied to the ram which, in turn, is dependent upon the pressure of the fluid and the control orifice through which the fluid flows. Hydraulic fluid is supplied to the hydraulic ram 41 by system including a pump 60, a line 61 from the pump to one end of the cylinder 42, a line 62 from the other end of the cylinder back to the pump 60 and a reversing valve 63 between the inlet and outlet of the pump for operating the ram in opposite directions. In addition, a throttling valve 64 is provided in at least one of the lines 61 and 62 for controlling the amount of hydraulic fluid flowing to the ram and thereby of speed of movement of the carriage 29 mounting the nozzle 18. The throttling valve 64, for simplicity of disclosure is illustrated as an orifice plate, having arcuate orifices 65 which cooperate with fixed orifices to reduce the area of the orifices as the plate is turned. The movable plate of the throttling valve 64 is connected to the horizontal rack 52 to change the speed of movement of the carriage 29 directly with the change in rotative speed of the workpiece 13. The control mechanism illustrated in FIGURE 2 operates automatically in response to the movement of the cam follower 45 to increase the rotative speed of the workpiece 13 and the longitudinal movement of the nozzle 18 in inverse proportion to decreases in the radius of the surface of the workpiece 13 being coated, as indicated in FIGURE 4, to relatively move the surface and nozzle in a helical path at a constant relative speed and pitch. In addition, the nozzle 18 always will be maintained at the same spaced relation to the surface by the cam follower 45 and depending rod 28. Thus, the nozzle 18 will deliver the atomized coating material onto the surface of the workpiece 13 in a helical pattern and at a uniform rate over the entire surface.

Other motor speed changing mechanisms may be used in place of the variable speed friction drive illustrated in FIGURE 2 for rotatting workpiece 13 and other hydraulic control mechanisms may be used in place of the flow control valve 64. The motor speed changing mechanism may comprise an electric control for changing the speed of the motor 57, or a control for changing the reduction gearing, or a control for changing the effective diameter of the driving pulley. Similarly, the control of the hydraulic ram 41 may take different forms.

FIGURE 5 illustrates an apparatus used for coating the inside surface of rocket motor casings in which the cam follower is in the form of an arm 70 projecting radially from a sleeve 71 mounted on and slideable along a control shaft 72. Sleeve 71 is keyed to control shaft 72 by a key 73 to rock the control shaft from the cam follower 70. The sleeve 71 constitutes a carriage, similar to carriage 29 in FIGURE 1, with the assembly of nozzle 18, tube 19, mixing chamber 20, feed rolls 26, 27 and driving motor 25 mounted on a radial arm 74 at one end of the sleeve 71. An additional adjustable arm 75 projects

from the arm 74 to permit adjustment of the height and angular position of the nozzle 18 for workpieces 13 of different sizes and shapes. The cam follower 70 engages the edge of a profile cam 46 the same as in FIGURE 1 with the edge thereof corresponding to the shape of the surface to be coated. Thus, as the sleeve 71 is moved longitudinally by the hydraulic ram 41, the cam follower 70 rocks the sleeve and nozzle 18 carried thereby to maintain the nozzle at a constant fixed distance from the surface to be coated.

The shaft 72 has crank arms 76 and 77 at one end which are connected to operate the control mechanisms for varying the speed of rotation of the workpiece 13 and the rate of lead of the nozzle 18 at rates inversely proportional to changes in the radial distance of the surface from its axis of rotation. The mechanism for changing the speed of rotation of the workpiece 13 is illustrated as a control box 78 having an adjustable arm 79 connected to the crank arm 76 on the shaft 72 by a link 80. Crank arm 77 on the shaft 72 is connected through linkage 81 to a pressure relief valve 82 in the hydraulic system for varying the pressure of the hydraulic fluid supplied to the ram 41.

In the embodiment illustrated in FIGURE 5, the hydraulic system comprises a tank 83 for hydraulic fluid, a motor driven pump 84, a supply line 85 for delivering the hydraulic fluid to one end of the hydraulic ram 41. The other end of the hydraulic ram is connected by fluid return line 86 back to the tank 83 and has a flow control valve 87 therein. The flow control valve 87 in return line 86 may be adjusted to produce any predetermined back pressure for a desired pitch and the valve 87 cooperates with the relief valve 82 for varying the pressure of the motive fluid to control the rate of flow of the hydraulic fluid and speed of operation of the hydraulic ram 41 and sleeve 71. The pressure relief valve 82 supplies hydraulic fluid at a pressure proportional to the radius of the surface being coated and with a fixed back pressure moves the sleeve 71 at a rate inversely proportional to changes in the radius of the surface being coated. Thus, the speed of operation of the ram 41 is varied in accordance with changes in radius of the surface being coated and cooperates with the change speed box 78 for rotating the workpiece 13 to relatively move the surface of the workpiece and nozzle 18 in a helical path at constant relative speed and pitch. A suitable reversing mechanism also is provided in the hydraulic system for returning the nozzle 18 to a starting position.

FIGURE 6 illustrates an auxiliary apparatus used in conjunction with the apparatus illustrated in FIGURE 5 to restore the nozzle 18 to any particular position at which the coating operation has been stopped to withdraw the nozzle 18. During a flame spray coating operation, it is sometimes necessary to interrupt the cycle because of malfunction of the spray nozzle. On such occasions it is essential that after repair the nozzle be returned to the exact position along the workpiece 13 where the operation was stopped. To this end, the sleeve 71 has spaced brackets 90 and 91 mounting a rod 92 in spaced parallel relation to the sleeve. A spool 93 is slidable on the rod 92 and adapted to engage an abutment 94. The abutment 94 may be fixed at a certain position so that the sleeve 71 moves relative to the spool 93 during an operating stroke. When the nozzle 18 is withdrawn for any reason, the spool 93 and abutment 94 are engaged so that after the nozzle is withdrawn it may be brought back to the same position by moving the sleeve 71 inwardly until the spool 93 and abutment 94 are engaged. Preferably, the abutment 94 is mounted on the rod 92 and the spool 93 mounted on a chain 95 extending around sprockets 96, one of which may be turned manually so that the operator may move the spool 93 into engagement with abutment 94. Thus the engagement of the abutment 94 with spool 93 permits the return of nozzle 18 to the exact position from where the nozzle was with-

drawn or to any other position he may select. The manually operable sprocket 96 is driven by a hand wheel 97 connected by gearing to a dial 98 which indicates in inches any position of the nozzle 18 along the workpiece 13.

FIGURE 7 illustrates the apparatus of FIGURE 5 applying a coating to the interior surface of a rocket engine casing 100 of a regenerative cooling type having a wall formed by a plurality of adjacent tubes 101. The rocket engine casing 100 may comprise the series of adjacent tubes 101 attached to each other in side-by-side relation, or may comprise inner and outer walls with the tubes 101 therebetween. With the form of rocket motor casing illustrated in FIGURE 7, the surface being coated may be cooled, or stated otherwise, maintained at a predetermined temperature by circulating coolant through the tubes 101. Several forms of construction having now been described in detail, the mode of operation of the apparatus is next explained.

The coating operation is necessarily dependent upon material to be coated and the coating material. If the workpiece 13 is the casing of a rocket engine and is to be coated with a refractory and erosion resistant metal oxide described and claimed in U.S. Patent 2,707,691, referred to above and known as Rokide, the preliminary steps will depend upon the material of the engine casing. For example, such engine casings are sometimes made of aluminum, steel or copper. It has been found that Rokide coating can be applied to an aluminum casing after cleaning and grit blasting the surface which provides a sufficiently rough surface for good bonding of the Rokide thereto. On the other hand, the surface of stainless steel remains so smooth that it has been found necessary to interpose a metalized surface between the stainless steel and Rokide coating. It also may be desirable to initially metalize the surface to be coated to prevent oxidation. If oxidation is not completely eliminated and prevented, the Rokide coating does not properly adhere to the base metal which considerably lessens its bonding strength. Copper is another material which requires metalizing prior to application of a Rokide coating.

When an intermediate metalizing step is required, the coating metal may be applied by the apparatus of the present invention. The coating metal in rod form is positioned between the feed rolls 26 and 27 of the motor feeding mechanism 25, see FIGURE 3, and extends through the tube 19 to the nozzle 18. Combustible gases, such as oxygen and a fuel gas are supplied to the mixing chamber 20 through the tubes 22 and 23. The gases burn at the nozzle 18 and diffuse in a spray pattern. The metal from the rod 21 to be sprayed is melted and atomized by the flame and sprayed by the blast of the gases against the surface to be coated. The workpiece 13 is rotated by its driving means and the nozzle 18 advanced by the ram 41 at varying speeds corresponding to the radius of the surface from the axis of rotation to maintain the relative speed and lead of the surface and nozzle substantially constant and the nozzle is at all times maintained at the same distance from the surface. Thus, the parts move in a helical path at a constant relative speed and pitch to produce a uniform coating on the surface. As explained above, the movement of the cam follower 47 or 70 on the profile cam 46 for maintaining the nozzle 18 at a fixed distance from the surface, also provides the control factor for varying the rotative speed of the workpiece 13 and lead of the nozzle 18 to produce a constant pitch. Thus, the apparatus of the present invention operates to uniformly coat the surface of the workpiece 13 with an intermediate metal coating. When a stainless steel casing 13 is to be metalized, a nickel-chromium alloy is used comprising 60% nickel, 15% to 16% chromium and the remainder iron. When a casing of copper is to be metallized, pure nickel (commercial grade) may be used.

After the intermediate metalizing step, Rokide coating

may be applied in the same manner as described with respect to the metal coating. When the Rokide coating is applied, the surface of the workpiece to be coated should be preheated to a temperature sufficient to keep the surface dry. In the form of the apparatus illustrated in FIGURE 1, the surface may be heated by a hot air blast prior to coating. With the form of workpiece 100 illustrated in FIGURE 7, hot water at a temperature of, for example, 140° F. is circulated through the tubes 101. Care must be taken to maintain the heating temperature below that at which the strength of the material of the casing is affected.

A rod 21 of Rokide coating is inserted in the feeding rolls 26 and 27 and through the tube 19 to the nozzle 18. A combustible mixture supplied to the mixing chamber 20 flows through tube 19 to nozzle 18 and is ignited. The flame melts and atomizes the Rokide and the blast of the flame from the nozzle 18 projects a uniform flame spray of the molten coating in a fixed pattern from the nozzle 18 as the workpiece 13 rotates and the nozzle 18 advances along the surface. As explained above, the nozzle 18 is maintained at a fixed distance from the surface to be coated by the cam follower 47 or 70 as controlled by the profile cam 46. In addition, the movement of the cam follower 47 or 70 controls the variable speed drives for rotating the workpiece 13 and the hydraulic ram 41 for advancing the nozzle 18 to maintain the relative speed and lead of the surface and nozzle constant. The coating operation is continued with the coating material being sprayed onto the surface of the workpiece 13 in a helical path of constant pitch to produce a uniform layer of the coating material throughout the length of the workpiece.

If for any reason the coating operation is stopped, the position of the spool 93 on the rod 92, see FIGURE 6, will indicate the position. After the nozzle 18 has been withdrawn and the malfunction remedied, the nozzle 18 is moved back to the position where the abutment 94 engages the spool 93 and the coating operation again initiated. To this end the abutment 94 may be initially adjusted along rod 92 for any particular workpiece and the spool 93 moved to any position corresponding to a particular position along the surface of the workpiece as indicated by the dial 98, after which, the abutment 94 is brought into engagement with the spool 93 to position the nozzle 18 at a desired location.

It will now be observed that the present invention provides an apparatus for applying a molten atomized coating uniformly on a surface of varying radial distances about an axis of revolution. It also will be observed that the present invention provides an apparatus for producing a flame spray of a normally solid material while the parts are moved relative to each other in a helical path at the same constant speed and pitch at different radial positions. It also will be observed that the present invention provides an apparatus for relatively moving a flame spray nozzle and surface to be coated so as to cause the nozzle to follow the irregular contour of the surface at the same distance therefrom. It will be still further observed that the present invention provides an apparatus which is of relatively simple and compact construction and one which is reliable in operation to apply a uniform coating on the surface of a workpiece.

While several modified constructions are illustrated and described, it will be understood that further changes may be made in the construction and arrangements of elements without departing from the spirit or scope of the invention. For example, it has been found advantageous to enclose the combustible mixture of oxygen and acetylene or other gas in an envelope of air also ejected from the nozzle. The envelope or curtain of air contains the flame cone and, by using suitable deflectors, various angles of the flame issuing from the nozzle can be achieved. Such control of the flame, in turn, controls the deposition of coating material on the surface being coated in a

very precise manner. Also the mounting of the spool and abutment illustrated in FIGURE 5 may be reversed. Therefore, without limitation in this respect the invention is defined by the following claims.

5 We claim:

1. Apparatus for coating a longitudinally extending surface concentric to an axis of revolution at varying radial distances therefrom with a flame spray of a solid material rendered molten by the flame comprising a tube 10 having a nozzle at one end, means for mounting the tube and nozzle for movement longitudinally of and toward and away from the axis of revolution of the surface to be coated, means for supplying a combustible mixture to the tube which burns at the outlet from nozzle, means for feeding coating material through the tube to the nozzle which is melted by the flame and propelled in a fine spray in a diverging pattern by the blast of the flame, a variable speed motor connected to rotate the surface to be coated at an angular velocity inversely proportional to changes in the radius of said surface from its axis of revolution to relatively move the nozzle and surface at a constant linear velocity therebetween, a variable speed motor connected to move the nozzle longitudinally of the surface to be coated at a velocity inversely proportional to changes in the radius of said surface to maintain a constant pitch between turns of the helical path traced by the nozzle on the surface, a profile cam having a contour corresponding to the surface to be coated, and a cam follower engaging the profile cam and connected to the nozzle and variable speed motors for maintaining the nozzle at a constant distance from the surface to be coated as it moves longitudinally thereof and maintaining a constant relative velocity and pitch of the nozzle and surface at all radial distances of the surface from the axis of revolution.

2. Apparatus for coating the longitudinally extending surface of a body which is concentric to an axis of revolution at varying distances along the body with a flame spray of a solid coating material comprising, means for mounting the body for rotation about the axis of revolution, a control shaft extending parallel to the axis of revolution of the body at one side thereof, a sleeve slidable longitudinally along the control shaft, a radial arm projecting from the sleeve, a mixing tube mounted on said radial arm and having a nozzle at its end which overlies the surface to be coated, means for supplying a combustible mixture to the tube which burns at the outlet from the nozzle, means for feeding a strip of the solid coating material through the mixing tube and nozzle which is melted by the flame and propelled in a fine spray in a diverging pattern by the blast of the flame, variable speed driving means for rotating the body relative to the nozzle, variable speed driving means connected to move the sleeve along the control shaft to apply the coating material on the surface in a spiral path, a contour cam having the contour of the surface to be coated, a radial arm projecting from the sleeve and having a cam follower engaging the contour cam for rocking the sleeve as it moves longitudinally along the control shaft to maintain the nozzle at a fixed distance from the surface, and linkage operated by the rocking of the sleeve to adjust the speed of the respective driving means whereby to rotate the surface to be coated and move the sleeve along the rotating surface at speeds inversely proportional to the distance of the surface from the axis of revolution to apply the coating material at a substantially constant rate to the surface.

3. Apparatus in accordance with claim 2 in which the driving means for moving the sleeve is a hydraulic ram, a hydraulic system for supplying fluid to the ram comprising lines to and from the ram and a pump connected to the lines, a valve in one of the lines for controlling the flow of hydraulic fluid and the rate of movement of the sleeve, and means actuated by the contour cam for operating the valve to move the sleeve at a rate inversely propor-

tional to the distance of the surface from the axis of rotation.

4. Apparatus in accordance with claim 3 in which the hydraulic system comprises a tank, one of the lines connecting the pump to one end of the hydraulic ram, another line connecting the other end of the hydraulic ram to the tank, the valve in one of the lines comprising a variable pressure relief valve in the line from the pump to the ram to control the pressure of the hydraulic fluid supplied to the ram.

5. Apparatus in accordance with claim 2 in which the sleeve mounts a rod in spaced parallel relation thereto, a spool on the rod, an abutment, and said abutment and spool being relatively movable along the rod to indicate a particular position of the sleeve whereby to adapt the nozzle to be returned to the exact location where a coating operation is stopped by moving the spool and abutment into engagement with each other.

6. Apparatus in accordance with claim 5 in which the spool is mounted on a movable conveyor for sliding movement along the rod, the abutment is fixed to the

rod, means for manually operating the conveyor to move the spool into engagement with the abutment, and an indicator cooperating with the conveyor to indicate the position of the abutment relative to the surface to be coated.
